T. W. SLACK,
AUTOMATIC PUMP AND WINDMILL CONNECTION,
APPLICATION FILED AUG. 11, 1917.

1,272,132.

Patented July 9, 1918.

UNITED STATES PATENT OFFICE.

THOMAS W. SLACK, OF FORT WORTH, TEXAS.

AUTOMATIC PUMP AND WINDMILL CONNECTION.

1,272,132.

Specification of Letters Patent.

Patented July 9, 1918.

Application filed August 11, 1917. Serial No. 185,739.

To all whom it may concern:

Be it known that I, THOMAS W. SLACK, a citizen of the United States of America, residing at Fort Worth, in the county of 5 Tarrant and State of Texas, have invented certain new and useful Improvements in Automatic Pump and Windmill Connections, of which the following is a specification.

10 My invention relates to automatic starters for windmills and more particularly to certain attachments which will automatically detach a motor-operated pump jack from a sucker rod and in quick sequence 15 automatically connect the connecting rod of a windmill to the sucker rod of the pump and in quick sequence automatically release the windmill for action; and the object is to provide simple devices for detaching a 20 pump sucker rod from a gasolene motor in case the gasolene motor stops running and then in the same operation automatically attach a windmill connecting rod to the sucker rod, and in the same operation 25 in quick sequence release the windmill so that the windmill will operate the pump. Other objects and advantages will be fully explained in the following description and the invention will be more particularly 30 pointed out in the claims.

Reference is had to the accompanying drawings which form a part of this application.

Figure 1 is a perspective view of a pump 35 jack operated by a gasolene motor, showing a portion of a windmill frame, and showing the mechanism, partly in section, for detaching the sucker rod from the gasolene motor and for making connection 40 with the windmill connecting rod, and for releasing the windmill for action. Fig. 2 is an enlarged side elevation of the means for making the connection with the windmill operating mechanism. Fig. 3 is a detail 45 view of the dogs shown in Fig. 2, showing how they connect with the windmill connecting rod. Fig. 4 is a detail view of the bearing attached to the sucker rod for the gasolene motor connection. Fig. 5 is a side 50 elevation of the gasolene motor connecting devices. Fig. 6 is an enlarged plan view of a portion of the connecting devices shown in Fig. 5. Fig. 7 is a plan view of the connecting devices shown in Figs. 4 to 6 inclusive.

Similar characters of reference are used

to indicate the same parts throughout the several views.

The drawings show a portion 1 of a windmill tower for illustrating my invention. 60 A gasolene motor 2 is shown. This motor 2 will not be described, as any gasolene motor may be used for the purpose. A pump cylinder 3 is shown with a sucker rod 4 of ordinary type. A pair of pitman rods or 65 arms 5 are pivotally connected to the motor driving gear of motor 2. The pitman rods 5 are pivotally connected to a yoke 6. The yoke 6 has a hinged member 7 and the two parts of the yoke are clamped on a bearing 8 which is made rigid with the sucker rod 4. This completes a description of the connection of the gasolene motor with the sucker rod for operating the pump with the gasolene motor. Means are provided for automatically detaching the gasolene motor from the pump sucker rod if the gasolene motor 70 stops running. The hinged member is detachably connected to the member 6. The hinged member 7 has a lug 9 which projects 75 horizontally in a slot in the member 6 and a pin 10 is projected down through the member 6 and through the lug 9 to lock the lug 9 in the slot in the member 6. The lug or pin 10 is operated by a lever 11 which 80 is fulcrumed on the member 6 and connected to the pin 10. The lever 11 is operated manually to set the pin 10 in place to lock the members 6 and 7 together.

A vertical pipe or cylinder 12 is located 90 at a convenient place about the pump. A weight 13 is vertically movable in the cylinder 12. A cord 14 is attached to the weight 13 and run over an idler 15 stationed on the upper part of the cylinder and then 95 extended to a drum 16 positioned near the bottom of the cylinder 12. During operation of the pump by the gasolene motor, the weight is supported in the upper part 100 of the cylinder by a spring-controlled stop 17. Means are provided for automatically drawing the stop 17 from under the weight 13. Water is discharged from the pump through a pipe 18 which discharges water 105 into a bucket 19. The bucket 19 is suspended over a tank 20 by a lever 21 which may be fulcrumed on the pipe 18. A weight 22 is adjusted on the other end of the lever 21 which will balance the weight of the bucket 110 of water. A cord 23 is attached to the lever 21 and run over an idler 24 and attached to the spring 25. Ordinarily the water will

fall in the bucket and overflow into the tank 20. The bucket is constructed with an opening in or near the bottom so that water will continually run through the bucket and will gradually run out of the bucket when the pump stops. When the water runs out of the bucket, the weight 22 will act on the lever 21 and pull on the cord 23 and cause the cord to pull the stop 17 from under the weight 13. The weight 13 will descend more or less slowly on account of the retarding effect of the cord 14 running over the idler 15 and being wound on the drum 16. A weight 26 is supported on a trip 27 which is pivotally mounted on the cylinder 12 and projects through a slot into the cylinder. A cord 28 is attached to the weight 26 and run over an idler 29 and connected to the lever 11. As the weight 13 descends, it will actuate the trip 27 to release the weight 26. The weight 26 will actuate the lever 11 to draw the pin 10 out of the lug 9 and thus release the hinged member 7 of the yoke from the bearing 8 on the sucker rod. A spring 30 will throw the member 7 to the dotted outline position shown in Fig. 7. At the same time a weight 31 attached to the member 6 of the yoke by a cord 32 will move the yoke member 6 slightly away from the bearing 8. These operations detach the gasoline motor from the sucker rod 4.

Means are also provided for automatically connecting the sucker rod 4, after it is released from the gasoline motor, to the windmill connecting rod 33. A casing or sleeve 34 is attached to the arms 35 which depend from the connecting rod 33. The sucker rod 4 moves freely through the sleeve 34 during the operation by the gasoline motor. Means are provided for automatically connecting the sleeve 34 to the sucker rod 4. Dogs 36 are pivotally mounted on the sleeve 34 and provided with shoulders 37 which are adapted to engage shoulders 38 in the sucker rod 4. The dogs 36 have slots 39 and locks 40 are attached to a pivoted bar 41 for holding the dogs 36 out of engagement with the sucker rod 4. The locks 40 are held in the slots 39 by a trip 42 which engages a stop 43 on the sleeve 34. A spring 44 attached to the bar 41 presses the trip 42 against the sleeve 34. A spring 45 attached to the sleeve 34 and to the bar 41 normally holds the locks 40 in the slots 39 and thus holds the dogs 36 out of engagement with the sucker rod. A weight 46 is suspended on the cylinder 12 by a trip 50 which is pivotally mounted on the cylinder 12 and projects within the cylinder. A cord 47 is connected to the weight 46 and run over idlers 48 and 49 and connected to the trip 42. As the weight 13 descends in the cylinder 12, after the operation of detaching the gasoline motor from the sucker rod 4, it will actuate the trip 50 to

release the weight 46. The weight 46 will actuate the trip 42 to release the bar 41. The spring 45 will draw the locks 40 out of the dogs 36 and springs 51 will thrust the dogs 36 into the notches 38 in the sucker rod 4 and hold the dogs in these notches and thus lock the windmill connection to the sucker rod 4. The windmill is held out of gear by the ordinary rod or cable 52 and a locking lever 53 is attached to the cable 52, as in ordinary operation. The lever 53 may be held by a spring clamp 54. A bell crank lever 55 is fulcrumed on an extension of the base of the cylinder 12 and one end projects into the cylinder and the other end projects out of the cylinder. A cord 56 is connected to the lever 55 and to a trip 57 which will throw the lever 53 out of the clamp 54 and release lever 53. When the weight 13 drops down on the lever 55, the windmill will be thrown in gear so that the windmill commences to run as soon as the wind begins to blow.

It will be noticed that all the operations are to be started by the descent of the weight 13. It is apparent that this weight may be permitted to drop by various other means and that various changes in the sizes, proportions, arrangement, and construction of the various parts may be made without departing from my invention. After the weight 13 has descended to its limit and it is necessary to disconnect from the windmill connecting rod, the weight 13 and other co-operating parts may be replaced manually. The sleeve 34 and other parts co-operating therewith may be restored to inoperative position manually.

What I claim is—

1. In a pump provided with a driving means consisting of a motor, means for connecting the sucker rod of the pump to said motor, actuating means consisting of a vertical cylinder and a weight movable in said cylinder, a tripping means mounted on said cylinder and operatively connected with said motor connecting means adapted to be actuated by said weight for automatically disconnecting the motor connecting means from said sucker rod, and a gravity actuating means for automatically releasing said tripping means.

2. In a pump provided with alternative driving means consisting of a motor and a windmill, means connecting said pump to the motor for operation of the pump, and means for maintaining the operative connection of the pump and the motor and for automatically disconnecting the motor from the pump in case the water stops flowing from the pump and for automatically connecting the windmill to the pump.

3. In a pump provided with alternative driving means consisting of a motor and a windmill, means connecting the motor to the pump for operation of the pump, actuating

means for disconnecting said motor from said pump and for connecting the windmill to the pump, and gravity actuated devices for automatically starting said actuating means in case the water stops flowing from the pump.

4. In a pump provided with alternative driving means consisting of a motor and a windmill, means connecting the motor to the sucker rod of the pump, actuating means for disconnecting the motor from the pump and for connecting the windmill to the sucker rod, and gravity actuated means for automatically starting the actuating means in case the water stops flowing from the pump.

5. In a pump provided with alternative driving means consisting of a motor and a windmill, means connecting the motor to the sucker rod of the pump, actuating means consisting of a vertical cylinder and a weight movable in said cylinder, means operatively connected to the motor connecting means and adapted to be actuated by said weight for automatically disconnecting the motor from the pump, connecting means carried by the windmill connection and adapted to be actuated by said weight for automatically connecting the windmill to the sucker rod of the pump subsequent to the disconnection of the motor from the pump, and gravity actuated means for starting

said actuating means in case the water stops flowing from the pump.

6. In a pump provided with alternative driving means consisting of a motor and a windmill, means for connecting the motor to the sucker rod of the pump, actuating means consisting of a vertical cylinder and a weight movable vertically in said cylinder, a tripping means mounted on said cylinder and operatively connected with said motor connecting means adapted to be actuated by said weight for automatically disconnecting the motor connecting means from said sucker rod, a sucker rod engaging means carried by the windmill connection and a tripping means mounted on said cylinder and operatively connected to said sucker rod engaging means and adapted to be actuated by said weight for automatically connecting the windmill connections to the sucker rod subsequent to the disconnection of the motor from the pump, means adapted to be actuated by said weight for throwing the windmill in gear, and a gravity actuated means for starting the operation of said actuating means if the water stops flowing from the pump.

In testimony whereof I set my hand, this 3rd day of August, 1917.

THOMAS W. SLACK.
